Primary Examiner — Cynthia M. Chin(74) *Attorney, Agent, or Firm* — Daryl R. Wright; Greg Carr(57) **CLAIM**

We claim the ornamental design for a model vehicle skid pad assembly, as shown and described.

DESCRIPTION

FIG. 1 is a lower, right, rear perspective view of a model vehicle skid pad assembly, according to our new design; FIG. 2 is a rear elevation view thereof; FIG. 3 is a front elevation view thereof; FIG. 4 is a right side elevation view thereof; FIG. 5 is a left side elevation view thereof; FIG. 6 is an upper plan view thereof; FIG. 7 is a lower plan view thereof; and, FIG. 8 is a lower, right, rear perspective environmental use view of the model vehicle skid pad assembly.

In the drawings, the broken lines showing features of the model vehicle skid pad assembly form no part of the claimed design.

The broken lines in FIG. 8 depict environmental subject matter that form no part of the claimed design.
